SLIDE RULE ATTACHMENT

Joseph J. Smidi, Portland, Oreg.

Application March 4, 1949, Serial No. 79,638

6 Claims. (Cl. 235—64.3)

1

The present invention comprises a characteristic accumulator for association with a slide rule, the purpose of the invention being to provide means whereby the operator of a slide rule may accumulate characteristic figures at each operation of a series of mathematical computations performed upon the slide rule so that he may be constantly aware of the size of the accumulated resultant. It is well known that the operation of a slide rule requires constant attention to the sizes of the various numerals being multiplied or divided. Usually the operator follows the operations mentally, and this is a frequent source of serious errors in slide-rule computing. If a large number of numerals are being multiplied together or divided into each other, or the calculation requires a mixture of multiplying and dividing operations, the operator may be required to keep a work chart wherein he roughly computes the size of the resultant. These computations require time and extra effort and must be carefully attended to in order to avoid inaccuracies. The object of the present invention is to relieve the operator of excessive mental or manual effort in determining the proper sizes of the resultants of complicated mathematical operations by providing means for accumulating the characteristic figures as each operation of a series is performed upon the slide rule.

The present invention is, in one sense, an adding machine, since it provides means whereby each operation of a manually engageable part results in the algebraic addition of the numeral one to a previously accumulated characteristic total. If an operation is such as to increase the characteristic by more than one an addition lever may be operated more than once, and if the operation results in the subtraction of more than one from the accumulated total characteristic a subtraction lever may be operated more than once. The principle of the foregoing is embodied in my prior patent, No. 2,418,910, issued April 15, 1947, for which application for reissue, Serial No. 70,421, was filed on December 30, 1948, and which was reissued as Re. 23,127 on June 21, 1949. In that patent the principle is embodied in a cursor for a slide rule. The present invention comprises a structure which may be attached to the slide rule and over which an enlarged cursor of the regular type may be fitted. The present embodiment of the invention has the advantage that the operating levers project beyond the ends of the slide rule in position to be readily engageable without releasing

2

the slide rule, whereas with the embodiment illustrated and described in the prior patent it is usually necessary for the operator to release the slide rule with one or the other hand in order to engage the operating levers of the characteristic accumulator. The present invention has the further advantage over the prior form in that the addition lever is always found in the same position at one end of the slide rule and the subtraction lever is always found in a corresponding position at the other end of the slide rule, so that the operation thereof becomes automatic through habitual use, whereas with the prior form it is necessary to move the hand to the position the cursor happens to occupy at the time while mentally guarding against operating one lever when it was intended that the other should be operated.

An object of the present invention is to provide a device of the character described which is easily formed of relatively few, sturdy and easily manufactured and assembled parts.

The objects and advantages of the present invention will be more readily understood by inspection of the following specification taken in connection with the accompanying drawing wherein like numerals refer to like parts throughout, while the features of novelty will be more distinctly pointed out in the appended claims.

In the drawing Fig. 1 is a plan view of the present invention, with parts broken away, the invention being shown attached to a skeletonized slide rule and embraced by a skeletonized cursor mounted on the slide rule;

Fig. 2 is a side view of the invention taken from the plane of the line 2—2 of Fig. 1;

Fig. 3 is a partial view of the invention, on an enlarged scale, taken from the line 3—3 of Fig. 1;

Fig. 4 is a section through the invention taken along the line 4—4 of Fig. 2;

Fig. 5 is a partial view similar to Fig. 4 showing the parts in another position at the end of an operative movement;

Fig. 6 is an end view of the invention shown in its position of attachment to a slide rule;

Fig. 7 is a section, on an enlarged scale, taken along line 7—7 of Fig. 5; and

Fig. 8 is a vertical section taken along line 8—8 of Fig. 5.

The preferred form of the invention comprises a channel-shaped housing including an outer channel-shaped member 10 and an inner channel-shaped member 11, the two members being spaced

apart by a strap 12 at each end thereof, the legs of each strap extending beyond the channel-shaped members to provide ears 13 through which a bolt 14 may be passed. The ears are set into depressions in the upper and lower graduated surfaces of the slide rule and the bolt passed through an opening through the slide rule. By such an arrangement the channel-shaped housing is positioned along one of the narrow longitudinal surfaces of the slide rule with its flanges directed toward the edges of the slide rule whereby the outer surfaces of the flanges form extensions of the graduated surfaces of the slide rule. In order that the channel members and the straps 12 may be held together, the same are united by rivets 15. Preferably the heads of the bolts 14, and the nuts thereon, are very thin and the rivets 15 are inset so as not to interfere with the operation of the usual cursor. The structure described provides a hollow space adjacent a narrow longitudinal edge of the slide rule enclosed by a double wall housing providing a channel-shaped space 16 extending the entire length of the slide rule except for the small portions blocked off by the straps 12.

A runner is mounted in the channel-shaped space, the same preferably being channel-shaped so as to have flanges 20, the bottom of the runner being provided with a plurality of evenly spaced openings separated by narrow straps 21 extending across the bottom of the channel-shaped space, the runner therefore being substantially a rack, or a member having a plurality of abutments evenly spaced longitudinally thereof. The runner is no greater in length than one-half of the length of the channel-shaped space 16 so that a central point of the runner may be displaced one-half of its length toward either end of the space 16 from a centered position. At least one of the flanges of the outer member 10 is provided with a window 22 at the longitudinal center thereof, and at least one of the flanges 20 is provided with a plurality of evenly spaced characteristic indicia 23 in position to be viewed through the window 22. As seen in Fig. 1, the characteristic indicia 23 preferably comprise a zero, which is located at the longitudinal center of the runner, a series of ascending positive numerals extending from the zero toward the right end of the runner, and a series of ascending negative numerals extending from the zero toward the left end of the runner. The indicia 23 are of such size as to be viewed singly through the window 22 and are evenly spaced along the flange of the runner, the spacing thereof preferably being equal to the spacing of the connecting straps 21.

A pair of operating levers or bars are provided, the same comprising a first, or addition, bar 24 extending from the right end of the housing and a second, or subtraction, bar 25 extending from the left end of the housing, each bar being preferably provided with an angularly directed tip so as to provide a flat surface for engagement with the tip of a finger. Since each bar and its associated parts is identical, only one, namely the second bar, is herein fully illustrated and described.

The bar 25 is slidably mounted within the channel-shaped housing, being retained against the bottom of the inner member 11 by a pair of U-shaped straps 26 and 27, the straps being retained in position by rivets 28 and 29 respectively, extending across the housing to brace the structure. The bar 25 is slideable longitudinally of the housing between the bottom of the inner member 11 and the bottoms of the U-shaped straps. The bar

is normally urged outwardly by a spring 30 hooked over the rivet 28 and having its other end attached to a screw 31 extending inwardly from the lower surface of the bar. The bar is limited in its outward movement by engagement of the bottom of strap 27 with the outer end of a pawl 32 mounted upon the inner end of the bar. The pawl is mounted upon the bar by a screw 33 passing through an enlarged opening in the outer end of the pawl into the bar and a second screw 34 passing through a second enlarged opening in the inner end of the pawl into the tip of the bar. A spring 35 is positioned between the head of screw 34 and the pawl so as constantly to urge the pawl toward the bottom of the channel-shaped housing. The tip of the pawl projects outwardly toward the connecting straps 21 so that, when permitted to do so, it may engage one of the straps whereby the runner may be moved longitudinally upon continued movement of the operating bar. In order to permit such engagement the bottom of the channel member 11 is provided with an opening 36, the opening being of such length that when the bar is projected outwardly to its limit of movement the dog 32 is cammed into the housing by a cam surface thereof engaging the outer end of the opening 36. On the other hand, when the operating bar is moved inwardly the pawl may enter one of the openings between a pair of straps 21, thereby to engage one of the straps and move the runner, the opening 36 being of such length as to limit movement of the runner to the distance required to displace one characteristic index with an adjacent characteristic index, the movement being limited by the pawl engaging the inner end of the opening 36. In Fig. 4 the opposed opening 37 is illustrated, this opening being identical to opening 36 and being provided for the purpose of permitting operation of a pawl 38 (Fig. 8) identical to pawl 32 and mounted upon the addition lever 24 in the identical manner as the first pawl is mounted upon the subtraction lever.

The operation is illustrated in Figs. 4 and 5. In Fig. 4 the pawl 32 is shown in withdrawn position in full line and in projected position in dotted line just before it engages one of the cross straps. In Fig. 5 the pawl is illustrated in the position at which further movement of the runner is limited by the pawl engaging the inner end of the opening 36.

The operation of the device is relatively simple and easily understood. Upon each inward movement of the addition bar 24 the runner is displaced toward the left by the distance between adjacent characteristic indicia, and upon each inward movement of the subtraction bar 25 the runner is displaced one characteristic toward the right. Therefore, if an operation of the slide rule requires increasing or reducing the accumulated characteristic by more than one, the appropriate bar is operated the appropriate number of times before the next operation of the slide rule. Therefore, any characteristic, either negative or positive, within the limits of size of the runner, may be accumulated, with the result being viewable through the window 22.

It is obvious that the opposite surface of the outer member 10 may have a window therein and the opposite flange 20 of the runner may have indicia thereon. Likewise, the window may be of such length as to permit viewing of more than one of the indicia, in which case it would be necessary to provide a cross-hair or reference mark to locate the resultant of a series of operations. A window of the size shown is prefer-

able so as to avoid the appearance of confusing numerals on the accumulator. Other modifications in arrangement and detail will be readily apparent to those skilled in the art, and I claim as my invention all such modifications as come within the true spirit and scope of the appended claims.

I claim:

1. A characteristic accumulator for association with a slide rule comprising an elongated, channel-shaped housing adapted to be attached to a slide rule along one of the narrow longitudinal surfaces thereof with its flanges directed toward the edges of the slide rule whereby the outer surfaces of said flanges form extensions of the graduated surfaces of the slide rule, said housing comprising inner and outer members spaced from each other to provide an enclosed space, a runner slidably retained in said space and comprising a plurality of abutments evenly spaced longitudinally thereof, said space being at least twice as long as said runner, said runner having evenly spaced characteristic indicia thereon and the outer member of said housing having a window therein through which said indicia may be viewed, a first bar slidably mounted for longitudinal movement in said housing and including a manually engageable portion projecting from one end thereof, a second bar slidably mounted for longitudinal movement in said housing and including a manually engageable portion projecting from the opposite end thereof, spring means in said housing urging said bars outwardly, means limiting outward movement of said bars, a first pawl mounted on said first bar and engageable with said abutments upon inward movement of said first bar, a first spring constantly urging said pawl toward said abutments, first retracting means to retract said first pawl from said abutments upon outward movement of said first bar to its limit of movement, first inward movement limiting means to limit movement of said runner in one direction upon each inward movement of said first bar to the amount required to displace one characteristic index with an adjacent characteristic index, a second pawl mounted on said second bar and engageable with said abutments upon inward movement of said second bar, a second spring constantly urging said second pawl toward said abutments, second retracting means to retract said second pawl from said abutments upon outward movement of said second bar to its limit of movement, and second inward movement limiting means to limit movement of said runner in the opposite direction upon each inward movement of said second bar to the amount required to displace one characteristic index with an adjacent characteristic index.

2. The structure set forth in claim 1 wherein said characteristic indicia comprise a series of positive numerals arranged in ascending order in one direction from a zero located at the longitudinal center of the runner and a series of negative numerals ranging in ascending order in the opposite direction from said zero.

3. The structure set forth in claim 1 in which said window is of such size as to permit viewing of one only of said characteristic indicia and said window is located at the longitudinal center of said housing.

4. A characteristic accumulator for association

with a slide rule comprising an elongated, channel-shaped housing adapted to be attached to a slide rule along one of the narrow longitudinal surfaces thereof with its flanges directed toward the edges of the slide rule whereby the outer surfaces of said flanges form extensions of the graduated surfaces of the slide rule, said housing comprising inner and outer members spaced from each other to provide an enclosed channel-shaped space, a channel-shaped runner slidably retained in said space and having a plurality of evenly spaced openings in the bottom thereof providing a plurality of abutments evenly spaced longitudinally thereof, said space being at least twice as long as said runner, said runner having evenly spaced characteristic indicia on at least one flange thereof and the outer member of said housing having a window in at least one flange thereof through which said indicia may be viewed, a first bar slidably mounted for longitudinal movement in said housing and including a manually engageable portion projecting from one end thereof, a second bar slidably mounted for longitudinal movement in said housing and including a manually engageable portion projecting from the opposite end thereof, spring means in said housing urging said bars outwardly, means limiting outward movement of said bars, the inner member of said housing having a pair of openings in the bottom thereof, a first pawl mounted on said first bar and engageable with said abutments through one of said openings upon inward movement of said first bar, a first spring constantly urging said pawl toward said abutments, the outer edge of said opening operating to retract said first pawl from said abutments upon outward movement of said first bar to its limit of movement and the inner edge of said opening engaging said pawl to limit movement of said runner in one direction upon each inward movement of said first bar to the amount required to displace one characteristic index with an adjacent characteristic index, a second pawl mounted on said second bar and engageable with said abutments through the other of said openings upon inward movement of said second bar, and a second spring constantly urging said second pawl toward said abutments, the outer edge of said other opening operating to retract said second pawl from said abutments upon outward movement of said second bar to its limit of movement and the inner edge of said other opening engaging said second pawl to limit movement of said runner in the opposite direction upon each inward movement of said second bar to the amount required to displace one characteristic index with an adjacent characteristic index.

5. The structure set forth in claim 4 wherein said characteristic indicia comprise a series of positive numerals arranged in ascending order in one direction from a zero located at the longitudinal center of the runner and a series of negative numerals ranging in ascending order in the opposite direction from said zero.

6. The structure set forth in claim 4 in which said window is of such size as to permit viewing of one only of said characteristic indicia and said window is located at the longitudinal center of said housing.

JOSEPH J. SMIDL.
